TOGGLE TYPE CONNECTING ASSEMBLY

Joseph S. Kessler, Kenosha, Wis., assignor to Tri-Clover Machine Co., Kenosha, Wis., a corporation of Wisconsin

Application January 20, 1951, Serial No. 206,947

2 Claims. (Cl. 24—68)

1

This invention relates to improvements in toggle type connecting assemblies, and more particularly to connecting assemblies for drawing and holding together the ends of a clamping band.

In industries, such as the food industry, wherein it is of utmost importance that sanitary conditions at all times prevail, the equipment used therein must be frequently disassembled and cleaned. To this end the equipment must be designed with a minimum of parts, said parts being associated in easily disassembled relationship and being devoid, as much as possible, of screw threading, corners, or other crevices where food particles may lodge.

Because it is particularly well adapted for sanitary applications, the V-type clamping band, used in connection with flanged coupling members, has replaced bolted type connections at many points in food handling equipment. While certain of the V-type clamping bands heretofore available have been provided with toggle type connecting assemblies, these connecting assemblies have not been entirely satisfactory because, as heretofore constructed, disassembly and cleaning have been difficult and time consuming.

It is, therefore, a general object of the present invention to provide an improved toggle type connecting assembly which is adapted for use on V-type clamping bands as well as in other applications, said assembly being so constructed that it may be quickly, easily, and completely disassembled.

A further object of the present invention is to provide an improved connecting assembly of the class described wherein the individual parts are substantially devoid of corners or crevices which might cause lodgement of food particles.

A further object of the invention is to provide an improved toggle type connecting assembly for a device which has a pair of relatively movable end portions which are to be drawn together wherein there is a novel coaction between the nose of the toggle handle and a lug on one of the end portions.

A further more specific object of the invention is to provide an improved toggle type connecting assembly for V-type clamping bands, said assembly having a bail connected to one end of the band and having a locking handle pivotally connected to said bail and engageable with the other end of said band but not positively connected therewith.

A further object of the invention is to provide an improved connecting assembly of the class described which is simple in construction, inex-

pensive to manufacture, and otherwise well adapted for the purposes described.

With the above and other objects in view, the invention consists of the improved toggle-type connecting assembly, and all of its parts and combinations, as set forth in the claims, and all equivalents thereof.

In the drawing accompanying and forming a part of this specification, wherein is shown one complete embodiment of the preferred form of the invention and wherein like characters of reference indicate the same parts in all of the views:

Fig. 1 is a side elevational view of the improved connecting assembly applied to a V-type clamping band and disposed in locked position;

Fig. 2 is a plan view of the clamping band and connecting assembly shown in Fig. 1;

Fig. 3 is a fragmentary vertical sectional view taken approximately along the line 3—3 of Fig. 2; and

Fig. 4 is a fragmentary transverse sectional view taken along the line 4—4 of Fig. 1.

Referring more particularly to the drawing, the numeral 5 indicates a conventional V-type clamping band which is preferably circular in outline. The band 5 is formed with a cylindrical peripheral wall portion 6 (see Fig. 4), having divergent inwardly extending annular wall portions 7 and 8, said wall portions at their inner edges being formed with oppositely projecting annular flanges 9 and 10 respectively. The band 5 is formed with a pair of juxtaposed opposite end portions 11 and 12. Diametrically opposite the end portions 11 and 12, a portion of the walls 7 and 8 and flanges 9 and 10 is cut away as at 13 to leave an extent of the wall 6 which is flexible.

Mounted on the end portions 11 and 12 respectively is a pair of lugs 14 and 15 which form a part of the improved connecting assembly. The lugs 14 and 15 are formed with lips 16 and 17 respectively which lips project in opposite directions in the plane of the band 5, the lugs being formed beneath said lips with transversely extending rounded grooves 18 and 19.

A locking handle 20 of irregular conformation is channel shaped in cross-section for the major portion of its length, and has a width greater than the width of the lug 15 and lip 17, as shown in Fig. 2. The handle 20 is formed at one end with a rounded nose portion 21 which is adapted to be pivotally seated in the transverse groove 19 of the lug 15, as shown. The handle 20 is formed in a portion of its web which is adjacent its nose 21 with an aperture 22, said aperture being so positioned and of such size as to receive the lip

17 as the handle 20 is swung outwardly about its nose when the latter is seated in the groove 19.

Spaced inwardly from the nose portion 21 the handle 20 is formed in its opposite side flanges with a pair of aligned apertures 23 and 24. An elongated, generally C-shaped bail 25 has a pair of inwardly directed end portions 26 and 27 which project inwardly through the apertures 23 and 24 respectively. The bail 25 also has a closed loop portion 28 opposite the end portions 26 and 27, the portion 28 being seated in the transverse groove 18 of the lug 14 below the lip 16 thereof. The lug 14 is formed with a vertical bore 29 spaced inwardly from the lip 16, which is adapted to removably yet snugly receive a retaining pin 30. The bore 29 and pin 30 are positioned to prevent removal of the bail 25 from the lug 14. The end portions 26 and 27 of the bail 25 are cut away as at 31 (see Figs. 2 and 3) to receive the side flange portions of the handle 20 adjacent margins of the apertures through which said bail ends project. The handle 20 may be formed with an enlarged aperture 32 in the web portion thereof adjacent the apertures 23 and 24, as shown.

When in locking position the handle 20 normally lies against the band 5. In this position the end portions 11 and 12 of the band 5 are rigidly held in relatively close relationship. To loosen the band 5 it is only necessary to swing the free end of the handle 20 outwardly away from the band 5, thereby pivoting the handle about its nose 21, the latter being seated in the transverse groove 19. This swings the end portions 26 and 27 of the bail upwardly and moves said bail toward the lug 14, thereby permitting lugs 14 and 15 and end portions 11 and 12 to move apart. As the handle 20 is swung in this manner, the lip 17 is received in the handle aperture 22. The handle 20 can be thereafter readily swung out of engagement with the lug 15 and lip 17. As the band 5 is removed from its operative position, one end of the bail 25 remains connected to the handle 20 while the other end remains connected to the lug 14 because of the retaining pin 30.

The handle 20 can be readily removed from the bail 25 by spreading apart the end portions 26 and 27 to remove the same from the apertures 23 and 24. Removal of the bail 25 from the lug 14 can be readily effected by removal of the pin 30. The completely disassembled parts can then be easily and quickly cleaned. Reassembly of the

parts is accomplished by a reversal of the operation just described.

Various changes and modifications may be made without departing from the spirit of the invention, and all of such changes are contemplated, as may come within the scope of the claims.

What I claim is:

1. A toggle-type connecting assembly for a clamping ring having a pair of relatively movable juxtaposed end portions to be drawn and held together, comprising: a first lip on one of said end portions directed away from said end portion; a second lip on the other of said end portions directed away from its end position, said lips projecting in opposite directions from each other; a handle having one end formed with a nose removably and pivotally seated under said second lip, said handle being formed with an aperture adjacent the tip of said nose which is positioned to receive said second lip as the handle is pivoted in one direction; and a bail pivotally connected to said handle and having a closed loop portion removably engaged below said first lip.
2. A toggle-type connecting assembly for a clamping ring having a pair of relatively movable juxtaposed end portions to be drawn and held together, comprising: a lip on one of said end portions projecting away from its end portion, a handle having one end formed with a nose removably and pivotally seated under said lip, said handle having an aperture adjacent the tip of said nose which is positioned to receive said lip as the handle is pivoted in one direction, and link means connecting said handle with the opposite end portion of the clamping ring for drawing the end portions of the clamping ring together when the handle is moved toward the ring.
